ALFRED F. MASURY, OF NEW YORK, N. Y., ASSIGNOR TO INTERNATIONAL MOTOR COMPANY, OF NEW YORK, N. Y., A CORPORATION OF DELAWARE.

SECURING DEVICE FOR GEARS.

1,143,720.

Specification of Letters Patent. Patented June 22, 1915.

Application filed January 2, 1914. Serial No. 809,872.

To all whom it may concern:

Be it known that I, ALFRED F. MASURY, a citizen of the United States, residing in the borough of Manhattan of the city of New York, in the State of New York, have invented certain new and useful Improvements in Securing Devices for Gears, of which the following is a specification, reference being had to the accompanying drawings, forming a part hereof.

This invention relates to transmission gearing and is concerned particularly with the driving bevel pinion and its supporting shaft by which the driving force is transmitted from the drive shaft to the jack shaft. Under such conditions of use economy of space is a desideratum second only to that of strength. Pinions are usually fixed on the driving shaft by means of splines or keys engaging with key-ways formed on the hub of the pinion but such key-ways, of course, reduce the strength of the pinion appreciably and consequently the pinion must be made relatively large to compensate for such weakness. This weakening effect of key-ways in hardened pinions is especially appreciable.

It is the object of the present invention to provide improved means for securing the pinion to the driving shaft by which the pinion is in nowise weakened and its engagement with the shaft is equally effective as that formed by the usual key-way and spline.

In accordance with the invention the pinion hub has formed in one end thereof a slot or slots to engage a projection or projections on the shaft. Preferably, the pinion is tapered interiorly so as to have a driving fit on a correspondingly tapered portion of the shaft and the pinion is maintained in its operative position by means of a nut threaded on the shaft and engaging that face of the pinion which is not formed with the annular flange above referred to.

Reference is to be had to the accompanying drawings for a detailed description of the invention in which—

Figure 1 is a view looking up into a gear casing from the underside thereof and showing a transmission gear to which the invention is applied. Fig. 2 is a detail view on a somewhat larger scale and partly in section showing a driving shaft on which a driving pinion is fixed and showing also

suitable bearings therefor such as are provided in the embodiment shown in Fig. 1. Fig. 3 is a detail view in section of the pinion removed from the shaft. Fig. 4 is an end view thereof indicating conventionally the teeth of the pinion.

Referring now to Fig. 1, it appears that extending into the crank case *a* is a drive shaft *b*, on the end of which is carried a gear *b'* which is constantly in mesh with a gear *c* carried by a lay shaft *c'* to which are also secured pinions *c''* adapted to be engaged by sliding gears *d* or splined on the independent main driving shaft *d''* to control the speed of the vehicle in a manner well known. As usual, the lay shaft *c'* may also carry a gear *c'''* with which meshes an idler gear *e* to permit the direction of rotation of the shaft *d''* to be reversed when the gear *d'* is moved into mesh with the idler gear. The shaft *d''* has secured theron a driving bevel pinion *f*, the teeth of which are in mesh with the teeth of a bevel gear *g* carried on the jack shaft *g'*, indicated in dotted lines.

The pinion *f* has formed on one end of its hub *f'*, between which and the shaft is a suitable clearance space *f''*, slots *f'''* adapted to engage lugs or projections, such as the usual splines *d''* secured to or integral with the shaft *d''*. In actual practice the shaft *d''* is preferably tapered, as at *d''*, and the hub of the pinion *f* is also tapered interiorly and smooth bored to have a close fit on the tapered portion of the shaft, the ends of the splines *d''* entering the milled slots *f'''* as the pinion is fitted on to the shaft. When in its normal position the pinion *f* may be locked against axial movement by means of a locking nut *h* threaded on the shaft *d''* and engaging the free end face of the pinion. To economize space the nut *h* preferably rests within a recess *f''* formed in said end face. In keeping with the general object of the invention to economize space without sacrificing strength the hub of the pinion *f* is extended to form a sleeve-like portion *f'* intermediate its ends on which may rest a bearing collar *i* constituting one of the members of any convenient type of bearing such as the roller bearing indicated generally herein by the reference character *k*.

Since the driving pinion serves to transmit driving force from the shaft *d''* to the jack shaft it is natural that it should be sub-

jected to severe strains and accordingly it becomes necessary not only that its inherent structure should be stout but also that it should be adequately supported by suitable bearings arranged in proximity to it. By eliminating the use of a key-way or other usual attaching means by which the pinion is affixed to the driving shaft, and thereby eliminating the weakening elements, it becomes possible to construct a pinion of relatively small external dimensions and thus place relatively substantial bearings within the limited space of the gear casing and in immediate proximity to the two faces of the bevel pinion. For instance, in the illustrated embodiment the roller bearing *k* completely encircles the hub of the bevel pinion close to its outer face and a second bearing *l* receives the free end of the shaft *d* which extends beyond the lock nut *h*. These bearings give the pinion *f* a perfectly uniform and substantial support and relieve it of unusual twisting and lateral stresses.

While the improved device will find a great range of usefulness in other fields, the peculiar conditions of use surrounding the construction and compact arrangement of

shafting and gearing within the gear casing of an automobile make the improved pinion of especial value in this art.

Modifications which may suggest themselves to skilled mechanics may be made without departing from the spirit of the invention.

I claim as my invention:

In a device of the character described, a tapered driving shaft, splines thereon, and a smooth bored beveled pinion tapered interiorly and carried on the tapered portion of the driving shaft and provided with a sleeve-like portion on an extension of one face, the sleeve having a plurality of longitudinal slots cut in its end and arranged in loose driving engagement with the splines, and a nut threaded on the driving shaft and bearing against the other face of the pinion to maintain the pinion in engagement with the splines.

This specification signed and witnessed this 30 day of December A. D. 1913.

ALFRED F. MASURY.
